LAWRENCE MARK CHARTRAND, OF EAST ST. LOUIS, ILLINOIS

COMBINATION RAILWAY-TRACK CLAMP

Application filed May 12, 1930. Serial No. 451,669.

This invention relates to certain new and useful improvements in combination railway track clamp, the peculiarities of which will be hereinafter fully described and claimed.

The main objects of my invention are: first, to provide an efficient rail clamp for securing the rail to a tie; secondly, to eliminate most of the usual fastening bolts and spikes at the rail joint and elsewhere; thirdly, to support the rail head firmly at said joint; fourthly, to combine such a clamp with the usual wood tie; fifthly, to provide such a clamp with detachable dowel pins insertable through the usual bolt holes in abutting rail ends and eliminate the usual angle fishplate; sixthly, and other features hereinafter described and claimed.

In the accompanying drawing on which like reference numerals indicate corresponding parts,

Fig. 1 represents a side view of my clamp and track rails mounted on a wood tie and constituting the preferred form;

Fig. 2, a plan view of a portion of Fig. 1; 25 Fig. 3, a reversed plan of the base plate of my clamp;

Fig. 4, a vertical section on the line 4—4 of Fig. 1;

Fig. 5, a similar view to Fig. 1, showing 30 my clamp combined with a metal tie;

Fig. 6, a plan view of a portion of Fig. 5; and

Fig. 7, a vertical section on the line 7—7 of Fig. 5.

35 My construction practically eliminates the usual spikes securing the base flanges of track rails to wooden ties, and also does away with the usual bolts and angle fishplates at abutting joints of track rails.

40 Referring to the drawing, the numeral 8 indicates track rails disposed a suitable gauge distance apart for a railway. Below each rail is located a base plate 9 secured to the tie and having at one end integral therewith 45 an upwardly extending jaw 10 extending over the base flange and upward to engage the underside of the rail head. A movable jaw is mounted on this base plate and consists of a head 11 extending over the base 50 flange and engaging the underside of the

rail head similarly to that of the fixed jaw 10. The movable jaw has a shank 12 extending at right angles from the head and the track rail and slideable between two upwardly extending lugs 13 integral with the 55 said base plate and located on the opposite side of the rail from the fixed jaw 10.

These lugs have horizontally aligned openings in a plane near the upper surface of said shank 12 in which shank is a slot 14 aligned with said openings in the lugs and having the edge towards the rail preferably beveled downward for engagement with a wedge key 15 likewise preferably beveled for engagement with the beveled surface of said slot 14. 60 This wedge key bears against the openings in the lugs and forces the movable jaw member against the rail and clamps the rail in cooperation with the fixed jaw 10 which forms a buttress. The bevel edges of the slot and 65 the wedge key tend to hold the shank flat upon the base plate, and the jaw head 11, combined with the fixed jaw 10, holds the track rail firmly in position on the base plate.

On the bottom of the base plate under the 70 rail is a downward projection 16, preferably rounded as shown in Fig. 3, adapted to be inserted in an auger hole bored in the top of the tie, as indicated in Fig. 1. The base plate and tie are securely bound together by a fastening such as a stirrup strap 17 passing under the tie and having its ends connected by a bolt 18 passing above the shank 12.

75 The base plate is preferably narrower than the tie as shown in Fig. 2, so that the legs of the stirrup strap will not contact with the sides of the base plate but will have an insulating space 19, Fig. 2. A wooden block 20' is also driven under the bolt 18 to insulate the base plate when desirable as in the case 80 when the rails are used to conduct electric current for block signal or other purposes.

85 This base plate is in duplicate under each rail as shown in Fig. 1, and the fixed jaw 10 is preferably on the corresponding side of the 90 rails, and the movable jaw is likewise located as shown in Fig. 1. The base plates have two downwardly depending arms 20 and 21 respectively adapted to be disposed along the 95 sides of the tie and ending in flanges 23 which 100

are also provided with insulating plates 24. Holes in the flanges are provided with fastening bolts 25 having insulating washers 26, as shown in Figs. 1 and 2. The middle of the tie is thus exposed, and promotes better contact of the respective base plates with the tie. The tie can spring up in the center without interfering with the base plates near the ends.

The insulating piece 24 or other filler between the end flanges 23 will vary in thickness, according to the shrinkage of the castings, and the wider gauge between the rails which is required upon a curved track. Thus said piece 24 serves as an adjustable filler as well as an insulation from electricity when so required.

The stirrup strap 17 is preferably located as shown, between the wedge key and the respective rail.

The abutting ends of the rails are provided with holes through the web for the insertion of bolts connecting angle fish plates in the usual construction. At least two of these holes at a rail joint are embraced by the jaws 10 and 11 of my clamp. Said jaws are provided with sockets 27 opposite these holes in which are located dowel pins 28 as shown in Fig. 2, when the rail joint is enclosed by the jaws. These sockets are elongated corresponding to the elongated holes in the usual fishplates as required for the expansion of track rails. The dowel pins are not used except when my clamp embraces a rail joint in which latter case they correspond to the bolts in the usual angular fishplates.

While my preferred form of clamp is used with a wood tie, I have also shown it in Figs. 5-7 as applied to a metal tie 29 having walls forming chambers as in Fig. 7.

I claim:

1. A combination railway track clamp comprising a clamp for each rail each consisting of a base plate having lugs and having a jaw integral with said plate and inclined upward and fitting the underside of the rail head and the top of the base flange and forming a buttress, a movable jaw forming the other clamping member and comprising a head fitting under the rail head and above the base flange on the opposite side of the rail and having a shank extending at right angles to the rail and provided with a wedge bearing shoulder, and a wedge key engaging said shoulder and said lugs, substantially as described.

2. A combination railway track clamp comprising a clamp for each rail and each consisting of a base plate connected to the other plate and supporting the adjacent rail, and each plate having a jaw integral with the base plate and forming a buttress and inclined upward to engage the underside of the rail head and top of the base flange and having upwardly extending lugs on the opposite side of the rail with aligned openings for a wedge key, and a matching movable jaw having a head to

engage the underside of the rail head and top of the base flange opposite said buttress and having a shank extending at right angles to said head and between said lugs, and a wedge key mounted in said openings and engaging said shank, substantially as described.

3. The combination with track rails disposed a suitable gauge distance apart forming abutting rail joints having the usual bolt holes in the rail web, and a wood tie, of a clamp for each rail, said clamps consisting of base plates mounted on the tie and supporting the adjacent rail joint and detachably connected together each plate having an upwardly extending jaw member integral therewith and engaging the underside of the rail head and top of the base flange, a movable jaw member having a head similarly engaging the opposite side of said rail, said jaws having sockets alining with the holes at the rail joint, and dowel pins mounted in said sockets and passing through said rail holes, and means to secure the movable jaw in clamping position, substantially as described.

4. The combination with track rails disposed a suitable gauge distance apart, and a wood tie, of a clamp for each rail each comprising a base plate mounted on the tie and below the rail and provided with clamping jaws for the adjacent rail and having a downward projection below the rail engaging an alining hole in the tie, and means to secure said base plate upon the tie and maintain the engagement of said downward projection therewith, substantially as described.

5. The combination with track rails and a wood tie, of base plates mounted on said tie and supporting said rails and having depending lugs extending alongside the tie and adjustably connected together near the center of the tie, — said base plates being provided with clamping jaws engaging opposite sides of the respective rail, and means to clamp said jaws upon the rails, substantially as described.

6. The combination with a track rail and a wood tie, of base plates mounted on the tie and supporting the adjacent rails and each provided with an integral jaw and a movable jaw, both jaws inclined upward from the base plate and engaging the underside of the rail head, means to clamp the movable jaw against the rail, and a stirrup strap extending under the tie and connected above the movable jaw and adapted to hold the movable jaw and base plate and tie firmly together, substantially as described.

7. The combination with track rails and a wood tie, of a base plate mounted between the tie and each rail and each base plate provided with fixed and movable clamping jaws and having depending arms extending toward each other and disposed on opposite sides of the wood tie and having adjacent

flanged ends near the center provided with bolt holes, insulating pieces mounted between said ends and at the outside of said flanges, bolts passing through said flanges and insulating pieces, and stirrups embracing the tie and extending above the plates and movable jaws and insulated therefrom, substantially as described.

8. The combination with a track rail and
10 wood tie, of base plates on said tie supporting
the rails and each having an integral
fixed jaw at one end engaging the underside
of the rail head and top of the base flange
and having on the opposite end upwardly
15 extending lugs with aligned openings, a movable
jaw having a head engaging the underside
of the rail head and the top of the base
flange on the opposite side of the rail from
the fixed jaw and having a shank extending
20 from the head between said lugs and pro-
vided with a slot on its upper surface, one
side of which is beveled, a wedge key mount-
ed in said aligned openings and having a
matching bevel engaging that of said slot in
25 the shank, and fastening means for each base
plate and located between said wedge and
the adjacent rail for securing the movable
jaw and base plate to said tie.

In testimony whereof I have affixed my
30 signature.

HERMAN WALTEMATE.
